LOCKING MEANS FOR COVERS FOR WATER BOXES

Thomas E. Bart, Cincinnati, Ohio, assignor to
The Murdock Manufacturing & Supply Company,
Cincinnati, Ohio, a corporation of Ohio

Application July 16, 1937, Serial No. 154,112

5 Claims. (Cl. 70—161)

This invention relates to covers for water-boxes and the like and more particularly to locking means for such covers.

The principal object of my invention is to provide a simple device for controlling access to the interior of a water-box and its contents.

Another object of my invention is to provide a lid for water-boxes and the like containing a simple locking device which will be flush with the exposed upper face of the lid when the same is in closed position.

In providing water-boxes with lids, it has heretofore been the practice to secure the lids to a housing member by means of bolts with nuts on the exterior end thereof or by means of padlocks or other key-controlled devices. Considerable difficulty has been experienced in that children and mischievously inclined people open such devices and turn on water supplies and leave them run as well as doing other improper things therewith. While it is possible to use padlocks or other key-controlled devices of that character for controlling access to the valve and water connections within such devices, practical considerations render such arrangements unsatisfactory because the key holes and the like might be plugged up with mud or something of that character, thereby making it rather difficult to open the devices.

According to the present invention, the above difficulties and disadvantages have been obviated by providing a device which permits easy access to the interior of the water-box by a simple arrangement of parts and which provides an effective locking means especially adapted to be utilized for controlling access to water-boxes and the like.

With the above and other objects in view, the invention consists in general of certain novel details of construction and combination of parts hereinafter fully described, and illustrated in the accompanying drawing.

These and other objects are attained by the means described herein and disclosed in the accompanying drawing, in which:

Fig. 1 is a top view of the device.

Fig. 2 is a bottom view of the opening key.

Fig. 3 is a side view of a portion of the key.

Fig. 4 is a top plan view of the locking mechanism.

Fig. 5 is a cross-sectional elevation showing the relation of parts of the locking members.

Fig. 6 is a cross-section taken on line 6—6 of Fig. 1.

55 In the embodiment of my invention shown in

the present drawing, there is provided a housing or casing 10, having a lid 11, which is hinged to the housing 10, in any suitable manner so that the same may be opened, and closed. At the side opposite the hinged connection to the lid of the housing 10, there is formed a depression or recess 12 in which is rotatably mounted a locking member 13. The member 13 should be of a thickness such that it will fit within the recess 12 when assembled with the lid, thereby making it impossible to manipulate the same by means of pliers or any other instrument that would permit the obtaining of a bite upon the member 13 if it projected above the surface of the lid 11. A passage 14 extends downwardly from the recess 12 and receives the stud 15 formed integral with the member 13. At the lower end of the stud 15 is a laterally extending lug 16 having an inclined upper face 17 adapted to cooperate with an inclined lower face 18 formed on a lug 170 cast integral with the member 13 and disposed within the recess 19 in the housing 10. The passageway 14 is provided with a lateral extension 20 in order to facilitate assembly of the member 13 in the lid 11. A ring-like retaining means 21 is mounted in an annular groove 22 in the stud shaft 15 and prevents separation of the member 13 from the lid 11.

As shown in Fig. 4, in the upper face 23 of the member 13 there is provided a key-receiving recess 24 which may be of triangular shape or any other shape. The recess 24 is preferably of such size and contour that the insertion of the ordinary plier handle or screw driver bit will not serve for rotating the member 13 in its seat in the lid 11. With a proper instrument, such as the key 25 shown in Figs. 2 and 3, adapted to fit within the recess 24, it is possible to effect a very substantial locking of the lugs 16 and 170 by reason of their inclined faces so that ordinary articles that might be available to children or mischievously disposed persons would be inadequate to disconnect the two lugs.

Referring to Fig. 6, the key 25 may be inserted in the key receiving recess 24 and rotated in a clockwise direction by means of a handle 26. The rotatable locking member 13 and stud shaft 15 are then turned until the inclined face 17 of the lug 16 is directly under and in engagement with the inclined face 18 on lug 170 carried by member 10. The device is thus locked. To unlock the device, the member 13 is rotated in an anti-clockwise direction, thereby disengaging the lugs 16 and 170 and permitting the lid 11 to be tilted back on its hinges so that a suitable tool 55

may be inserted in the opening 28 and used to manipulate a valve located therein.

It will thus be seen that I have provided a simple and efficient device of the kind described above and for the purpose indicated herein.

The foregoing detailed description has been given for clearness of understanding only and no unnecessary limitations should be understood therefrom, but it should be construed as broadly as permissible in view of the prior art.

What is claimed is:

1. In a device of the class described, a lid for closing a hollow housing including a lug having an inclined lower face, a recess in said lid, a passage provided with a lateral extension extending downwardly from said recess for insertion of a laterally extending lug on a locking member, a rotatable locking member mounted in said recess and having a top surface in alignment with the surface of the lid, a stud shaft extending through said passage and integral with said locking member, and having at its lower end a laterally extending lug having an inclined upper surface adapted to register with the inclined lower face of said housing lug, and means on said shaft to prevent the separation of said locking member and said lid, and closing the lateral extension of the passageway against movement therethrough of the laterally extending lug when the parts are assembled.

2. In a device of the class described, a closure member for a hollow housing including a lug having a lower face inclined between the lateral edges thereof, said member having an opening therethrough, said opening being enlarged at the outer face of said member and having a lateral extension at one side thereof, a locking member having a head adapted to be received in said enlarged portion of the opening through the closure member and comprising a stud portion projecting from said head and a laterally extending lug formed on said stud at the free end of the stud, said lug being of a shape and size such that it may pass through the lateral extension of the opening through the closure member, the stud having an inclined face on the side thereof adjacent to the head, the stud and lug being of such sizes that the lug, when passed through the opening in the closure member may be disposed adjacent the lug on the housing with the inclined faces on said lugs in substantial parallel relation and in frictional contact whereby to secure the closure member in the open side of the housing,

and retaining means carried by the stud portion of the locking member, intermediate the lug and head thereof for precluding entry of the lug on the locking member into the lateral extension of the opening in the closure member, whereby to avoid separation of said members.

3. In a device of the class described, a housing lid comprising a hinge and an apertured depending boss at opposite sides thereof, the aperture of the boss comprising a lower keyhole-shaped portion and an enlarged upper circular recess in registering relationship, a latch member rotatable in said aperture and comprising a shaft, a laterally extending lug on one end of the shaft insertable through the keyhole portion of the lid aperture, a circular head on the other end of the shaft and closely fitting the circular upper recess of the lid to preclude the insertion of prying instruments therebetween, said head having a non-circular key receiving recess including side walls of enlarged proportions and spacing.

4. In a device of the class described, a housing lid comprising a hinge and an apertured depending boss at opposite sides thereof, the aperture of the boss comprising a lower keyhole-shaped portion and an enlarged upper circular recess in registering relationship, a latch member rotatable in said aperture and comprising a shaft, a laterally extending lug on one end of the shaft insertable through the keyhole portion of the lid aperture, a circular head on the other end of the shaft and closely fitting the circular upper recess of the lid to preclude the insertion of prying instruments therebetween, said head having a non-circular key receiving recess with straight-sided walls angularly disposed out of parallelism.

5. In a device of the class described, a housing lid comprising a hinge and an apertured depending boss at opposite sides thereof, the aperture of the boss comprising a lower keyhole-shaped portion and an enlarged upper circular recess in registering relationship, a latch member rotatable in said aperture and comprising a shaft, a laterally extending lug on one end of the shaft insertable through the keyhole portion of the lid aperture, a circular head on the other end of the shaft and closely fitting the circular upper recess of the lid to preclude the insertion of prying instruments therebetween, said head having a non-circular key receiving recess including straight-sided walls of enlarged proportions arranged at acute angles to one another in triangle formation.

THOMAS E. BART.
